US0D1078811S

(12) **United States Design Patent** (10) **Patent No.:** **US D1,078,811 S**
(45) **Date of Patent:** **** Jun. 10, 2025**

(54) **RELAY**

(71) Applicant: **Sung-Jen Wu**, New Taipei (TW)
(72) Inventor: **Sung-Jen Wu**, New Taipei (TW)
(73) Assignee: **SONG CHUAN PRECISION CO., LTD.**, New Taipei (TW)

(**) Term: **15 Years**

(21) Appl. No.: **29/823,085**

(22) Filed: **Jan. 14, 2022**

(51) LOC (15) Cl. **13-03**

(52) U.S. Cl.

USPC **D13/159; D13/158**

(57) **CLAIM**

The ornamental design for a relay as shown and described.

DESCRIPTION

FIG. 1 is a perspective view of a relay showing my new design;

FIG. 2 is a perspective view from another angle of view thereof;

FIG. 3 is a perspective view from the other angle of view thereof;

FIG. 4 is a reference perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is a perspective view of one component of the relay, shown separately to show aspects of the design that are not visible when combined;

FIG. 12 is a perspective view from another angle of FIG. 11; FIG. 13 is a perspective view of another component of the relay, shown separately to show aspects of the design that are not visible when combined;

FIG. 14 is a perspective view from another angle of FIG. 13; FIG. 15 is a perspective view of another component of the relay, shown separately to show aspects of the design that are not visible when combined; and,

FIG. 16 is a perspective view from another angle of FIG. 15. The broken lines in the FIGS. 1-10 illustrate portions of a relay which form no part of the claimed design.

1 Claim, 14 Drawing Sheets
